United States Patent Office

Des. 197,012
Patented Dec. 3, 1963

197,012

TELEPHONE HEADSET

Henry Dreyfuss, South Pasadena, Calif., and Norman C. Hazell, Freehold, N.J., assignors to Bell Telephone Laboratories, Incorporated, New York, N.Y., a corporation of New York

Filed Dec. 10, 1962, Ser. No. 72,789

Term of patent 14 years

(Cl. D26—14)

FIG. 1

FIG. 2

FIG. 1 is a perspective view of a telephone headset, showing our new design;

FIG. 2 is a perspective view showing the opposite sides;

FIG. 3 is a fragmentary front elevational view, to an enlarged scale, showing the inner side of the combined earphone, microphone and support therefor;

FIG. 4 is a fragmentary bottom plan view, to an enlarged scale, showing the combined earphone, microphone and support therefor; and

FIG. 5 is a fragmentary side elevational view, to an enlarged scale, showing the combined earphone, microphone and support therefor.

We claim:

The ornamental design for a telephone headset, as shown and described.
